Primary Examiner — Vy N Koenig*Assistant Examiner* — Qiawen W Wiechert(74) *Attorney, Agent, or Firm* — Ricky Lam(57) **CLAIM**

The ornamental design for a charging station nightstand, as shown and described.

DESCRIPTION

FIG. 1 is a front perspective view of a charging station nightstand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The evenly dashed broken lines in the drawings illustrate the portions of the charging station nightstand, which form no part of the claimed design.

The long dash-short dash broken lines encircling the enlarged views are for annotative purposes only and form no part of the claim.
